PRESSING MACHINE AND BUCK

George W. Johnson, Cincinnati, Ohio, assignor to
 The American Laundry Machinery Company,
 Norwood, Ohio, a corporation of Ohio

Application July 18, 1934, Serial No. 735,798

13 Claims.

(Cl. 38—20)

This invention relates to a pressing machine of the type used in laundry and garment work and particularly to a machine adapted to cause a pressing effect simultaneously in two directions, that is to say, one pressing effect generally in a plane and a side pressing effect at an angle to said plane.

One object of the invention is to provide novel means for pressing garments of the general type of men's shirts, wherein provision is made for pressing the front or back of a shirt body and simultaneously to press a portion of the side of the body so that the entire body of the shirt may be pressed in two lays.

A more specific object of the present invention is to provide a pair of cooperating pressing members each having a central portion and depending side portions, means for causing relative approach between the members so that the central portions of the members are in pressure engagement while the depending side portions are in position to coact and following which, pressure between the coacting central portions causes movement of the side portions into pressure engagement.

Another feature of the present invention is the provision of a pressing member mounted on a support, said member having a central pressing portion and side portions adapted to move laterally relative to the central portion, there being a yieldable connection between the member and its support and means for moving the side portions laterally into pressing coaction with another member by movement of the first member towards its support.

Another feature of this invention is the provision of an elongated pressing bed or buck having a substantially flat central portion and depending side portions having a hinged connection with the central portion.

Other objects and advantages of the invention will appear, including the provision of power means for the operation of a pressing machine of the above described type, one embodiment of which is shown in the accompanying drawing and described in the following specification.

In the drawing, Fig. 1 is a side elevation, partly broken away and diagrammed, illustrating a machine embodying my invention, together with control means therefor; Fig. 2 is an enlarged fragmental section through the bed and chest members, showing portions of the construction more in detail; while Fig. 3 is a plan view of the pressing bed.

I have illustrated my invention as applied to a

press of the scissors type comprising a frame 10 on which is mounted a pedestal 11 carrying a pressing buck or bed indicated generally at 12. An upstanding bracket 13 on the frame pivotally supports a head lever 14 which carries a head or chest 15 adapted to coact with the bed and which may be provided with heating means as desired. The head is movable toward and from the bed by means of toggles 16 and 17 extending between the frame 10 and the rear end of the head lever and movable toward straightened position by a cylinder and piston motor 18. For illustrative purposes only I have shown a cylinder 19 pivotally mounted on trunnions 20 and provided with a piston 21 having an operative connection by 15 means of piston rod 22 with the toggle mechanism.

Suitable control means is provided for supplying fluid under pressure to the motor 18, that illustrated comprising a two-hand control mechanism wherein valve casing 23 encloses a normally closed inlet valve 24 and valve casing 25 encloses a normally closed intake valve 26 and a normally open exhaust valve 27, the valves 26 and 27 being mounted on a common stem for joint operation. Control members 28 and 29 are provided for actuation of the valves in casings 23 and 25 respectively. The supply of pressure fluid is by way of conduit 30, valve 24, conduit 31, valve 26 and conduit 32 to the forward end of cylinder 19. Both control members must be depressed to provide a fluid flow and the depression of control member 29 will close exhaust valve 27 at the same time as intake valve 26 is opened, all as will be readily understood, as such arrangement is old in the art. Upon the supply of pressure fluid to motor 18, the piston moves rearwardly thus straightening the toggle mechanism and causing relative approach between the head and bed members. As the pressing members reach closed position, the piston uncovers a port 33 in the cylinder which communicates by way of conduit 34 with fluid pressure actuated holding means 35 and 36 located in valve casings 23 and 25 respectively, and operable upon the supply of pressure fluid thereto to maintain the control members in their operated position, whereupon the operator may release the control members. Upon completion of the pressing operation the operator raises control member 29 against the pressure of holding means 36, thus permitting the return of exhaust valve 27 to its normally open position which exhausts the fluid from motor 18, whereupon a

spring 37 connected between the rear end of the 45

head lever and the frame will return the members to open position.

This invention provides a pair of coacting pressing members suitable for pressing the body of a man's shirt and therefore of the elongated type familiar to the art and provided with central pressing portions and depending side portions of lesser area than the central portion and adapted to press certain of the side portions of a shirt simultaneously with the pressing action between the central portions. In accordance with my present invention, I provide a unitary member, in the present case the head member, with a central portion 38 and depending side portions 39 extending at an angle to the general plane of the central portion thereof. The coacting bed member is provided with a central portion 40 mounted on the pedestal or support 11 with provision for relative motion therebetween and biased 20 away from the support, as for instance by means of spring 41. Depending side portions 42 are provided on the bed having hinge or pivoted connections 43 with the central portion. Preferably a common cover means is provided for the central 25 and side portions of the bed which, as illustrated, comprises spring padding 44 and a cover cloth 45, although it will be well understood that other cover means is within the scope of my invention.

Means is provided for utilizing the pressure between the central portions of the pressing members when they are once brought into pressure engagement for moving the side portions of the bed into pressing engagement with the coacting side portions of the head. The specific means 30 illustrated comprises links 46 pivotally connected at 47 with the side pressing portions of the bed and extending toward the support and inclined downwardly when the bed side portions are in their retracted position. These links are pivotally 35 connected at 48 with the bed support 11. It results from this construction that when the yieldable connection between the bed and its support is taken up by the pressure engagement between the head and bed, the links 46 move 40 45 toward straightened position, as illustrated in broken lines in Fig. 2, thus causing the depending side pressing portions 42 of the bed to move into pressure engagement with the coacting side portions 39 of the head. Upon release of the pressure 50 fluid from motor 18 as the parts of the press move toward open position, the first movement is a separation of the bed 12 from its support 11 caused by the spring 41 which releases the pressure between the side pressing portions, whereupon further movement of the pressing members 55 completely opens the press.

With the parts in the position of Fig. 2, it will be noted that the greater the pressure between the central portions, the greater is the pressure between the side portions, due to the lateral movement of points 47.

What I claim is:

1. In a press of the class described, the combination of coacting elongated head and bed members each having a central pressing portion and side pressing portions, the side portions of said bed member being movable laterally outward relative to the central portion thereof, supports for said members, said bed member being movable relative to its support, means for causing pressure engagement between the central portions of said members, and means operable upon movement of said bed member relative to its support by pressure on the central portion of said bed member for moving the side portions thereof

laterally into engagement with the side portions of said head member.

2. In a press of the class described, a pair of cooperating elongated pressing elements relatively movable into and out of pressure engagement, supports for said elements, operating means for causing said relative movement to close and open the press, said elements comprising coacting portions successively contacting upon press closure and including primary contacting portions and secondary contacting portions, said primary contacting portion of one of said elements being movable relative to its support upon movement of the operating means in press closing direction, and means operable by said movement of said primary contacting portion relative to its support for moving said secondary contacting portions into pressure engagement.

3. In a press of the class described, the combination of elongated coacting pressing members each having a central portion and depending side portions of less area than said central portion, supporting elements for each of said members, one of said members having its depending side portions arranged for lateral movement relative to the central portion thereof whereby said member is variable in lateral extent, there being a yielding connection between one of said members and its supporting element, means for causing relative approach between supporting elements whereby to move said one member relative to its supporting element, and means operable by said relative movement of said one member for causing relative movement of the side portions of said laterally variable member with respect to the central portion thereof whereby to move said side portions into pressing engagement with the coacting side portions of the other pressing member.

4. In a press of the class described, the combination of coacting elongated members each having a central pressing portion and side pressing portions, supports for said members, the central portion of one of said members being movable relative to its support, one of said members having its side portions arranged for lateral movement relative to the central portion thereof whereby said member is variable in lateral extent, means for causing relative approach between said supports whereby to cause engagement of said central portions, and means operable by relative movement between said movable central portion and its support for causing relative movement of the side portions of said laterally variable member with respect to the central portion thereof, whereby to move said side portions toward the coacting side portions of the other pressing member.

5. In a press of the class described, the combination of elongated head and bed members each having a central pressing portion and depending side pressing portions, supports for each of said members, said bed member having its side portions arranged for angular movement relative to the central portion thereof, there being a yielding connection between said bed member and its support, said connection biasing the bed member away from its support, means for causing relative approach between said supports whereby to move said bed member toward its support, and means operable by said bed movement for causing relative movement of the side portions of said bed member with respect to the central portion thereof whereby to move said bed member side portions toward the coacting side portions of the head member.

6. In a press of the class described, the combination of coacting elongated head and bed members each having central pressing portions and depending side pressing portions, the side portions of said bed member being constructed and arranged for lateral movement relative to the central portion thereof, a support for said bed member, there being means permitting relative motion between said bed member and its support, rigid means connected at one end with a side portion of the bed member and at its other end to a fixed member below the central portion, said rigid means sloping downwardly from its first named connection, and means for moving said bed member toward its support by pressure of the head member thereon.

7. In a press of the class described, the combination of coacting elongated head and bed members each having central pressing portions and side pressing portions, the side portions of said bed member being hinged to the central portion thereof whereby said side portions are movable to extended and retracted positions, a support for said bed member, there being means permitting relative motion between said bed member and its support, a link having one end pivotally connected with one of said bed side portions and having its other end pivotally connected with said bed support, said link sloping downwardly toward said support when said bed side portion is in its retracted position whereby movement of said central portion of said bed member toward its support causes said link to move said side portion of the bed member into pressure engagement with the coacting side portion of the head member, and means for pressing said head member against the central portion of said bed member.

8. In combination, a buck having a central portion movably mounted relative to a support and side portions supported for lateral movement relative to said central portion, and means operable by relative movement between said central portion and its support for moving said side portions laterally.

9. A pressing buck having a central pressing portion adapted to iron a shirt front, separate side portions depending at an angle to said central portion and movable laterally relative thereto,

to, and common cover means for said central and side portions.

10. A pressing buck having an elongated central pressing portion, separate side portions movable laterally relative to said central portion, and common cover means for said central and side portions.

11. In a press of the class described, the combination of a pair of coacting elongated pressing members, one of said members having a central portion and a plurality of side portions movable laterally relative to said central portion and into engagement with coacting portions of the other pressing member when said members are in pressing position, means for causing coacting pressure engagement between the central portions of said members, and equalizing means interconnected between said portions for equalizing the pressure exerted upon the various portions by engagement of the members.

12. In a press of the class described, the combination of a pair of coacting elongated pressing members each having a central portion and side portions disposed at an angle to the general plane of said central portion, the side portions of one member being laterally movable relative to the central portion thereof, the central portion of said one member being movable relative to its support, power operated means for causing pressure engagement between said central portions and for moving said movable central portion relative to its support, and means responsive to movement of said central portion of said one member for moving said movable side portions into engagement with the corresponding side portions of the other member.

13. In a pressing machine, a pair of cooperating pressing members each having a central pressing portion and a plurality of coacting side pressing portions depending from said central portion, means for causing pressure engagement between some of said portions, one of said engaged portions being movable relative to its support, and means controlled by said relative movement of said movable engaged portion for causing pressure engagement between other of said portions.

GEORGE W. JOHNSON.
